CLAIM

The ornamental design for a safety wall plate, as shown and described.

DESCRIPTION

FIG. 1 is a perspective view of a safety wall plate in accordance with my new design;

FIG. 2 is a front view thereof;

FIG. 3 is a top view thereof;

FIG. 4 is a bottom view thereof;

FIG. 5 is a left side view thereof; and,

FIG. 6 is a right side view thereof.

The broken lines represent unclaimed subject matter and form no part of the claimed design. The back of the safety wall plate is not visible during use and forms no part of the claimed design.

1 Claim, 2 Drawing Sheets
